Inventor:
John J. Crowley
by Right from Quincy May
Attest.

UNITED STATES PATENT OFFICE.

JOHN J. CROWLEY, OF CAMBRIDGE, MASSACHUSETTS.

POWDER DISPENSER.

Application filed June 20, 1924. Serial No. 721,207.

To all whom it may concern:

Be it known that I, JOHN J. CROWLEY, citizen of the United States, residing at Cambridge, in the county of Middlesex and

5 State of Massachusetts, have invented new and useful Improvements in Powder Dispensers, of which the following is a specification.

This invention relates chiefly to means for 10 dispensing talcum and other toilet powders.

One object of this invention is to provide a dispenser including a powder reservoir, a distributing nozzle, and an air ejector co-operating with the reservoir and nozzle in 15 such manner that a forcible discharge of powder from the reservoir through the nozzle may be caused by air forced by said ejector without liability of escape of powder from the reservoir when the ejector is not 20 in operation.

Another object is to provide a dispenser characterized as above stated, the distributing nozzle being adapted to cause the scattering or wide distribution of the discharged powder, so that a considerable area 25 may be quickly and evenly powdered.

Of the accompanying drawings forming a part of this specification,—

Figure 1 shows in longitudinal section, 30 a powder dispenser embodying the invention, a portion of the air ejector and the air nozzle being shown in elevation.

Figure 2 is a section on line 2—2 of Figure 1.

35 Fig. 3 shows partly in section and partly in elevation, a different and the preferred construction of the distributing nozzle.

Figure 4 is an enlargement of a portion of Figure 3.

40 Figures 5 and 6 are views similar to Figure 3 showing modifications.

The same reference characters indicate the same parts in all of the figures.

In the drawings, 12 designates an air 45 nozzle which may be a length of tubing of any suitable material. The air nozzle is enclosed for the major portion of its length in a powder reservoir 13, preferably cylindrical and of glass or other suitable material. In this instance, one end of the reservoir is formed by a head 14 screwed upon the body of the reservoir, as shown by Figure 1, the other end of the reservoir being formed by a breast 15 which may be integral 50 with the body, as shown by Figure 1, or detachably secured thereto, as shown by Fig-

ure 3. The breast is provided with a distributing nozzle 16. The nozzles 12 and 16 are arranged in tandem order, so that they constitute a practically continuous conduit. 60 The distributing nozzle 16 includes a contracted intake portion 17, a contracted outlet portion 18, and an intermediate enlarged portion or chamber 19. While the distributing nozzle may be substantially spherical, 65 as shown by Figure 1, I prefer to form it as shown by Figure 3, the breast 15 forming one wall of the enlarged portion or chamber 19. With the air nozzle 12 is associated an air ejector 20 which may be a normally 70 expanded compressible rubber bulb having the usual valve adapted to admit air when the bulb expands and to be closed when the bulb is compressed to force air through the air nozzle. As here shown, the bulb is provided with a neck 21 secured upon a threaded nipple on the head 14. The intake end portion of the air nozzle passes through a stuffing box 22 on the head, preventing air 75 forced by the ejector from entering the reservoir.

I provide means for permitting a limited flow of powder from the reservoir to the distributing nozzle, the arrangement being such that air forced through the air nozzle induces a flow of powder from the reservoir into the distributing nozzle and ejects it 80 from the latter.

In the preferred arrangement shown by Figures 1, 3 and 4, the discharge end of the air nozzle 12 is seated on the breast around the contracted portion 17, and is provided with notches 23 constituting vents through which a limited quantity of powder passes when air is forced through the air nozzle. 85 In the arrangement shown by Figure 5, the discharge end of the air tube is slightly spaced from the portion 17 to form an annular vent 24. In the arrangement shown by Figure 6, the discharge end of the air nozzle is seated on the bore portion 17, and is provided with orifices 25 constituting vents wholly within the air nozzle. It will be seen that the reservoir has a powder outlet formed either by a plurality of vents or by 90 a single annular vent communicating with the distributing nozzle, and of relatively small capacity, which is much smaller than that of the air nozzle. The result is that a jet of air forced through the air nozzle sucks 95 powder into its path and forces the powder through the distributing nozzle. Owing to 100 105 110

the relatively small capacity of the outlet connecting the reservoir with the distributing nozzle, there is no liability of accidental escape of powder from the reservoir. 5 The powder laden air expands in the portion or chamber 19, so that the powder is agitated and held in suspension in said chamber. The air is compressed before passing through the outlet portion 18 and expands in leaving said outlet portion, so that the powder is scattered in the form of a fine mist or spray. The dispenser is therefore well adapted for distributing or dusting toilet powder evenly on large surfaces 10 of a human body, and may be manipulated to powder the back as well as the front portions of the body.

I claim:

A powder dispenser comprising an air

nozzle, a powder reservoir enclosing the air 20 nozzle, and having a distributing nozzle aligned with the air nozzle, and an air ejector associated with the air nozzle, means being provided for permitting a limited flow of powder from the reservoir into the distributing 25 nozzle, the arrangement being such that air forced through the air nozzle induces a flow of powder from the reservoir and ejects the powder from the distributing nozzle, said distributing nozzle having a contracted 30 intake portion, a contracted outlet portion, and an intermediate enlarged chamber portion, the nozzle being adapted to cause an agitation of powder forced through it and the scattering of the discharged powder. 35

In testimony whereof I have affixed my signature.

JOHN J. CROWLEY.
